ELEVATOR DOOR CONTROL

Christian Nielsen, Chicago, Ill., assignor to Illinois
Elevator Company, Chicago, Ill., a corporation
of Illinois

Application February 5, 1931, Serial No. 513,553

3 Claims. (Cl. 268—53)

This invention relates primarily to door controls and particularly to the automatic operation and control of doors used in conjunction with automatic elevators.

5 The object of the present invention is to provide for the automatic opening and closing of the elevator door, after the elevator has arrived at the floor level or before it leaves the floor level in such manner that the operation of the door will be 10 full, free and complete as well as safe.

With the above and other objects in view, as will be apparent, this invention consists in the construction, combination and arrangement of parts, all as hereinafter more fully described, 15 claimed and illustrated, in the accompanying drawings, wherein:

Fig. 1 is an elevation of an elevator car illustrating the inner-door thereof under the control of the present invention;

20 Fig. 2 is a plan view of the present control; Fig. 3 is an elevation thereof; and

Fig. 4 is a similar view taken from the opposite end of the control and illustrating the operation of the retiring cam, controlling the lock of the 25 floor opening door.

The present invention is designed to provide for the mechanical opening and closing of the inner-door of an automatic elevator: i. e. that door attached to the elevator car itself, under the control of a motor which in turn is operated by various electrical connections and circuits which form no part of the present invention but which are regulated by and from the elevator control. Thus, when the elevator car arrives and stops at 30 a floor level the present invention is set in motion and will open the door attached to the car, and when the car proceeds in its movement after the closing of the floor door, the present invention, prior to any movement on the part of the car, will close the inner or car door. The present invention also controls or regulates the retiring cams which in turn release the locks of the door acting as a closure for the floor opening, whereby the same may be opened.

40 References being had more particularly to the drawings 10 designates an automatic elevator car provided with the collapsible door 11. This door 11 is provided with a cam-bar 12 which in turn controls a switch 13, whereby the circuit for the 45 operation of the car is broken or made.

Mounted upon the roof of the car 10 in substantial alignment with the door 11 is a frame 14 or superstructure, at one end of which is a motor 15 driving, through the medium of a flexible connection 16, a shaft 17 threaded, as at 18,

throughout a major portion of its length. This shaft 18 is journaled adjoining its ends in suitable bearings 19, which are connected by a bar 20, extending from one bearing to the other.

A block or carriage 21 is mounted upon the shaft 18 and is provided with an interiorly threaded aperture, through which the threaded portion 18 of the shaft 17 operates, so that if the shaft rotates in one direction the carriage 21 will travel along the shaft 18 in a corresponding direction and when the shaft 18 rotates in the opposite direction the movement of the carriage 21 will be reversed.

To prevent any turning of the carriage 21 upon the shaft 18 and to insure its longitudinal movement along said shaft between the bearings 19, a series of rollers 22 are mounted upon one face of the carriage 21, two of the rollers 22, operating upon the upper edge of bar 20 and the remaining two rollers operating along the lower edge of the bar 20. Thus the co-operation between the rollers 22 and the bar 20, located between the two individual sets of rollers, overcomes any tendency of the carriage 21 to swing in either direction with the rotation of the shaft 18.

A U-shaped frame 23 is secured to the upper end of the carriage 21 and at its ends is provided with vertical arms 24.

Two parallel shafts 25 are interposed between the arms 24 of the frame 23, upon which operates 30 a slide 26, slidably carrying an outwardly projected stud 27. Interposed between the arms 24 of the frame and the outer faces of the slide 26, are a series of coil springs 28, encircling the shafts 25 and so situated upon said shafts that 35 irrespective of the direction of the movement of the slide 26 it operates against the tension of two of the springs 28.

Carried by the frame 14 and extending below the same in a plane, approximating the center of 40 the threaded portion of the shaft 18, is a hanger 29 to which is pivoted medially at its ends, a lever 30. The upper end of the lever 30 is pivotally connected to the stud 27 of the slide 26 and its lower end is connected by means of the pitman 45 34 to the door 11.

Thus it will be seen, by referring to Fig. 1, that if the motor 15 operates in one direction the carriage 21 will travel upon the shaft 18 toward the motor 15, thereby opening the door 11 and when 50 the motor 15 operates in the reverse direction the carriage 21 will operate upon the shaft 18 in a direction away from the motor 15 thereby closing the door 11. The opening and closing of the door 11 operates the well known switch construc- 55

tion 12—13, by which the electricity for the operation or movement of the elevator is controlled. By the provision of the springs 28 an element of safety is created in the present invention which will prevent damage to passengers in the car 10 as well as to the mechanism of the car. Should an obstruction of any kind be interposed in the path of the door 11 either in opening or closing, the continued movement of the carriage 21 will be compensated for by the springs 28, thereby preventing damage to the obstruction.

To control the operation of the motor 15 in connection with the limits of the movement of the door 11 a cam 32 is secured to the lower end 15 of the carriage 21 and is designed to co-act with standard switches 33 mounted on the frame 14. These switches 33 are adjustable and as the carriage 21 reaches the limit of its movement along the shaft 18 in closing or opening the door 11, the 20 cam 32 contacts with either of the switches 33 and regulates the flow of current operating the motor 15 so that when the door is either closed or opened to its limit as determined by the adjustment of the switches 33, the motor 15 will not 25 continue in its operation.

In all automatic elevators, there is a door upon the car 10 as illustrated by the door 11 and also a door at each floor so that the floor opening is always closed except when a car is positioned at 30 the floor opening. These outer doors acting as closures for the floor opening are each controlled by a latch 34 under the control of a roller 35, which when operated permits the door at the floor opening to be opened either from the interior or exterior of the car 10 and which when not operated, causes the outer door to remain locked. These latches 34 are operated by a retiring cam on the car 10 which constitutes a shoe 36 mounted on pivoted parallel levers 37 carried by the 35 car. If the shoe 36 is projected into the path of a roller 35 it will operate the coacting latch 34 when the car has been positioned at the floor opening, thereby permitting the outer door to be opened. If, however, the shoe or retiring cam 40 45 36 is not projected into the path of the roller 35, the position of the latch 34 will remain unaltered and consequently the coacting floor door cannot be opened.

The present invention in addition to automatically opening and controlling the inner door 11 of the elevator car 10 is designed to regulate and control the position of the retiring cam or shoe 36, so that when the motor 15 becomes energized to open the door 11 after the car has become positioned at the floor opening, the cam or shoe 36 will be positioned for co-action with the roller 35. This is accomplished by a bell crank lever 38 pivoted to the frame 14 adjoining the end thereof adjacent to the shoe or retiring cam 36. One arm of this lever is connected by a link 39 to the upper end of the lever 30, while the opposite arm of the bell crank 38 is connected by a pitman 40 to the shoe or retiring cam 36. Thus when the carriage 21 moves to the right, as illustrated in Fig. 1, the link 39 moves in a similar direction, moving the pitman 40 down-

wardly thereby lowering the parallel links 37 and forcing the shoe or retiring cam 36 into the path of the roller 35. Reversely as the upper end of the lever 30 moves to the left (Fig. 1) a pull is exerted upon the link 39 elevating the pitman 40 and links 37, thereby swinging the shoe or retiring cam 36 away from and out of the path of roller 35.

From the foregoing it is apparent that the present invention provides an automatic means for opening and closing the door 11 carried by the car 10, which is entirely safe in its operation and which is capable of adjustment to determine the limits of movement of the door. It is furthermore manifest that the present invention provides an automatic means which will regulate the position of the retiring cam directly from the control and operation of the car door.

What is claimed is:

1. The combination with an elevator car, of a 20 door carried thereby, a frame mounted on said car in substantial alignment with the door aforesaid, a motor mounted on said frame, a threaded shaft driven in either direction by said motor, bearings for said shaft, a bar extending from one 25 of said bearings to the other, a carriage having threaded co-operation with the threaded shaft aforesaid, rollers projecting from said carriage and disposed above and below the bar aforesaid, a frame carried by said carriage, parallel shafts 30 mounted in said frame, a slide mounted on said shafts, a stud slidably carried by said slide, springs interposed between said slide and the ends of said frame, a fixed hanger, and a lever pivoted 35 respectively to said slide, said hanger and said door.

2. The combination with an elevator car, of a 40 door carried thereby, a frame mounted on said car in substantial alignment with said door, a motor mounted on said frame, a threaded shaft 45 driven by said motor in either direction, bearings for said shaft, a bar interposed between said bearings, a carriage having threaded connection with said shaft, rollers projecting from said carriage and disposed above and below said bar, a 45 U-shaped frame carried by said carriage, parallel shafts mounted in the arms of said frame, a slide mounted for reciprocation upon said shafts, springs on said shafts and interposed between the arms of said frame and said slide, a stationary hanger carried by the first said frame, a door operating lever pivoted to said hanger, a slideable pivoted connection between the upper end of said lever and said slide.

3. The combination with an elevator car, of a 55 door carried thereby, a screw threaded shaft mounted upon the car in substantial alignment with the door, a motor adapted to rotate this shaft in either direction, a carriage adapted to be moved longitudinally of this shaft by means 60 of this rotation, a slide mounted upon said carriage, a stud engaging this slide, a fixed hanger, and a lever being pivoted on this fixed hanger, operatively engaging the door and carrying the aforementioned stud.

CHRISTIAN NIELSEN.
